UNITED STATES PATENT OFFICE.

EDWARD CLIFF, OF NEWARK, NEW JERSEY.

DESIGN FOR A CASING FOR SIDE BEARINGS FOR CAR-TRUCKS.

SPECIFICATION forming part of Design No. 25,958, dated August 18, 1896.

Application filed July 16, 1896. Serial No. 599,447. Term of patent 14 years.

To all whom it may concern:

Be it known that I, EDWARD CLIFF, a citizen of the United States, residing at Newark, in the county of Essex and State of New Jersey, have invented and produced a new and original Design for the Casing of a Side Bearing for Car-Trucks, of which the following is a specification, reference being had to the accompanying drawings, forming a part thereof, and in which—

Figure 1 is a side elevation of a casing for a side bearing incorporating my design; Fig. 2 is a top view of same, and Fig. 3 is a longitudinal section of same on the dotted line 3 3 15 of Fig. 2.

The leading features of my design consist of the elements hereinafter described, and the whole being as shown in the accompanying drawings.

In the drawings, A B respectively designate the upper and lower parts of the casing, which, whether viewed from the sides or top, is composed of the two circular sections C D, which merge into one another at the center of the casing on the harmonious inwardly-curved lines E. The sides of the upper and lower

parts A B, in addition to being composed of the two circular sections C D, have the upwardly and inwardly inclined or tapered sides, the sides of the lower part B being outward beyond the sides of the upper part A, as shown. The tapered sides of the lower part B rise from a flat surrounding base F. At the ends of the lower part B are hollow angular ribs G, extending to the upper edge 35 of said part and closed at their upper end, and on the ends of the upper part A at the lower edge only of the latter are the hollow angular projections H, which are smaller in cross-section than said ribs and enter the 40 same.

What I claim is—

The design for the casing of a side bearing for car-trucks, substantially as shown and described.

Signed at New York, in the county and State of New York, this 15th day of July, 45 A. D. 1896.

EDWARD CLIFF.
